(57) **CLAIM**

The ornamental design for a self-service storage cabinet as shown and described.

DESCRIPTION

The patent or application file contains at least one drawing executed in color. Copies of this patent or patent application publication with color drawing(s) will be provided by the Office upon request and payment of the necessary fee.

1. Self-service storage cabinet

1.1: Front

1.2: Back

1.3: Left

1.4: Right

1.5: Top

1.6: Bottom

1.7: Perspective

1.8: Perspective

1.9: Perspective

1.10: Perspective

1.11: Perspective

The present design is for a self-service storage cabinet. The portions of the article shown in the colors yellow and green form no part of the claimed design.

1 Claim, 11 Drawing Sheets
